UNITED STATES PATENT OFFICE.

JOSEPH J. EVANS, OF NORTH TONAWANDA, NEW YORK.

TUMBLER-WASHER.

SPECIFICATION forming part of Letters Patent No. 602,190, dated April 12, 1898.

Application filed July 2, 1897. Serial No. 643,316. (No model.)

To all whom it may concern:

Be it known that I, JOSEPH J. EVANS, a citizen of the United States, residing at North Tonawanda, in the county of Niagara and 5 State of New York, have invented a new and useful Improvement in Tumbler-Washers, as set forth in the annexed specification and drawings.

My invention has for its object to provide 10 a simple, efficient, and rapid means for washing and cleansing tumblers used at soda-water fountains and other drinking-places.

Referring to the accompanying drawings, in which like notation designates similar 15 parts, Figure 1 is a vertically longitudinal sectional view of my invention through the line O P of Fig. 2, while Fig. 2 is a cross-sectional view through the line M N of Fig. 1, both of which will be hereinafter more fully 20 set forth.

In reducing my invention to practice I provide a stationary brush D, secured to a suitable shell L, embracing the apparatus, and adjacent to this stationary brush is provided 25 a rotary brush C, adapted to be revolved by the water-wheel B, mounted upon the same horizontal shaft and situated within the casing A, said casing having an injection-pipe I and a discharge-opening F leading into the 30 tumbler K being cleansed and also into the brush C, which I prefer to make open-work or hollow. The casing A is provided also with an overflow G and a deflector-plate J, adjacent to the pipe F, for directing the wa- 35 ter into it, this latter being more clearly shown in Fig. 2, to which I will now refer.

The action of my invention is as follows: Water being admitted by the inlet at I to the wheel B causes its rotation, which rotation 40 causes a corresponding rotary movement of the brush C, over which the tumbler K to be cleansed is held, and is thus cleaned under the combined action of the brush and the flushing of the water discharged from F. After 45 the interior of the glass is cleaned, if it is held lightly on the rotating brush C by a slight pressure at its center, it will revolve

freely with the brush C and its exterior cleansed by the stationary brush D, which is secured to the shell L by the spring E, and 50 is provided with a projection H, which when pressed against by the tumbler forces the brush against the tumbler's exterior, thus insuring a good contact between the two.

In case the discharge-water at any time 55 cannot be carried off by the discharge F it will back up in the casing A until the overflow G is reached, when the surplus will be carried off without going into the tumbler.

Having thus fully described the nature and 60 object of my invention, what I claim, and desire to secure by Letters Patent, is—

1. In a tumbler-washer, the combination of a casing provided with a water-inlet, a stationary brush attached to said casing, a hollow rotary brush mounted on a shaft journaled in the casing, a water-wheel on said shaft within the casing, a discharge-pipe leading from the casing to the interior of said hollow brush, and a deflecting-plate within the 70 casing adjacent to said wheel, for deflecting discharge-water into the discharge-pipe, all substantially as described.

2. In a tumbler-washer, the combination of a casing provided with a water-inlet, a stationary brush attached to said casing, a hollow rotary brush mounted on a shaft journaled in the casing, a water-wheel on said shaft within the casing and a discharge-pipe leading from the casing to the interior of said 80 hollow brush, substantially as described.

3. In a tumbler-washer, the combination of a casing containing a rotary water-motor, a hollow rotary brush operated by said motor, a spring-supported stationary brush attached to the casing adjacent the rotary brush and a projection on the stationary brush adapted to be engaged by the article being cleansed and thereby force the brush against its exterior surface, substantially as described.

JOSEPH J. EVANS.
